UNITED STATES PATENT OFFICE.

NICHOLAS MILLER, OF CHICAGO, ILLINOIS.

STAMP-AFFIXING DEVICE.

1,418,600.

Specification of Letters Patent. Patented June 6, 1922.

Application filed June 2, 1917. Serial No. 172,389.

To all whom it may concern:

Be it known that I, NICHOLAS MILLER, a subject of the King of Hungary and Emperor of Austria, residing at Chicago, in 5 the county of Cook and State of Illinois, have invented certain new and useful Improvements in a Stamp-Affixing Device.

The purpose of this invention is to affix adhesive stamps or labels to envelopes and 10 other suitable articles and to deliver stamps, tickets or like articles. The main objects of my invention are the following:

(1) To provide guides to aid in fastening the stamps at any desired place on an envelope or article and to provide means to aid in fastening a series of stamps side by side. (2) To provide a novel and simple device for moistening the stamps. (3) To provide a counter to count the stamps as 20 they are used, provision being made to render the counter inoperative when there are no stamps in the apparatus. (4) To provide means to count and deliver any desired number of stamps without being moistened when it is desired to stamp mail or packages not suited to the apparatus. (5) To provide such an apparatus with a safety device to render it inoperative when the envelope or other article is not in its proper 30 place. (6) To provide a combination lock device for locking or unlocking the door through which the machine is supplied with stamps and to lock the door against operation simultaneously with the locking of the door when desired. (7) To provide an apparatus of this kind with a stamp affixing member which will press the moistened stamp on the envelope or other article and will automatically adjust itself to the irregular surface caused by the enclosed matter. Other new and useful inventions 40 will appear in describing the apparatus, the appended drawings and in the claims.

In order that my invention may more 45 clearly be understood reference is to be had to the accompanying drawings forming part of this specification and in which

Figure 1 represents a partial front view showing location of counter.

50 Figure 2 shows the side view giving location of door with combination lock device.

Figure 3 is a rear view of the apparatus giving side view of the combination lock device, also location of water reservoir.

Figure 4 is a top view of the apparatus.

Figure 5 shows an envelope with a series of stamps attached side by side by this device.

Figure 6 is a side view of the apparatus 60 showing the mechanism assembled, also the stamp roll in position.

Figure 7 is a rear view of the apparatus with part of the casing cut away to show the assembled mechanism. 65

Figure 8 is a partial side view showing the stamp feeding, counter mechanism and moistening device.

Figure 9 is a front view of the feeding ratchet and related mechanisms. 70

Figure 10 is a top view of the stamp channel which co-operates with the feeding ratchet and moistening device.

Figure 11 is a front view of the knife blade and moistening device. 75

Figure 12 is part of Figure 8 in a different operative position.

Figure 13 shows the stamp channel in position to receive the stamps.

Figure 14 is a partial enlarged front view 80 of the stamp feeding ratchet.

Figure 15 is a side view of Figure 14.

Figure 16 is a partial enlarged front view of the moistening device.

Figure 17 is a side view of Figure 16. 85

Figure 18 is a partial enlarged front view of a modified form of moistening device.

Figure 19 is a sectional view of Figure 18 on line "B B".

Figure 20 is a side view of the safety lock 90 device and of the mechanism for delivering stamps without moistening.

Figure 21 is the side rear view of Figure 20.

Fig. 21^a is a partial isometric view of 95 Fig. 21 showing the relation of parts 35, 45, and 48.

Figure 22 is part of Figure 20 in a different operative position.

Figure 23 is an axial section on line "C C" 100 Figure 24 of the self-aligning stamp affixing member.

Figure 24 is a sectional top view of Figure 23 looking in the direction "A A".

Figure 25 is a partial front view of Figure 105 23.

Figure 26 is a top view of the guide mechanism for the envelopes. The frame work is supposed to be removed.

Figure 27 is a front view of Figure 26. 110

any water escaping from it even when level of water in reservoir is higher than level of mouth of cell. Thus it is seen that when the stamp band is moved along in contact 5 with the water cell 21, a film of water will be drawn on the adhesive side of the stamp.

The purpose of blade 22 is to break up any gummy or sticky substance that might adhere to the mouth of the cell and thus insure 10 the stamp band's being wetted by the moistening cell 21. The valve device shown in Figures 18 and 19 is to prevent the escape of any water from the reservoir even if the apparatus should be held in different positions or violently shaken. Thus it has been 15 shown how the stamp band is advanced and moistened preliminary to being sheared off and fastened upon an envelope.

Now the shearing device and means for 20 fastening a stamp upon the envelope will be described. A stamp affixing member 37 is supported on end of shaft 25, Figures 20 and 21. The construction of this member 37 is best shown in Figures 23, 24 and 25. Member 37 is provided with a projection 37^a forming a seat for a ball 38. A sliding piece 39 is guided in a hole in end of member 25 and forms another seat for ball 38. A spring 40 pushes down upon piece 39. Member 37 is also provided with edges 37^b 25 and recessed portions 37^c, Figure 24. Shaft 25 has projecting edges 25^b which engage edges 37^b of member 37. Slots 37^c are provided for assembling shaft 25 and member 37. Thus it is seen that spring 40 holds member 37 firmly against shaft 25 through overlapping edges 25^b and 37^b. The purpose of ball 38 is to hold member 37 central with shaft 25, also to permit some motion of member 37 in any direction when spring 40 is compressed by depression of shaft 25 and overlapping edges 25^b and 37^b are separated.

A slotted projection 37^e is also provided on member 37, the lower portion of the slot 45 being somewhat enlarged (Figure 25). A pin 41 secured to shaft 25 guides member 37 into its original position when pressure upon shaft 25 is removed. 42 is a knife element fastened to member 37 and co-operates with knife element 19, shearing off individual stamps from stamp band. The manner in which member 37 aligns itself to an envelope is shown in Figure 20. Envelope 43 is shown having an uneven surface due to the matter inside and member 37 aligning itself to the inclination of the envelope while pressing the adhesive stamps upon it.

The operations thus far can be summarized as follows: Upon depression of knob 32, stamp is brought into engagement with mouth of water cell 21, a further movement of knob causing the stamp to be fed forward by stamp feeding member 15 and a 65 film of water is drawn upon adhesive side

of stamp. (See Figure 12.) A still further movement of knob will cause knife element 42 upon member 37 to shear off the moistened stamp and member 37 will press stamp upon the envelope. On releasing 70 knob, spring 44 will restore mechanism to its normal position.

A safety device to render the apparatus inoperative when there is no envelope or other article in its proper place will now be 75 described. On bracket 35, Figures 20, 21 and 21^a a bar 45 is slidably mounted by shoulder screws 46 and 47. Lower end of bar 45 is bent as shown at 45^a. A lever 48 is pivotally supported on bracket 35. A projection 48^a, Figures 20 and 21^a bears upon a lip 45^b of bar 45 through spring 49. Opposite bent portion 45^a is a depression 1^a, see Figures 4, 6, 7 and 20, into which bent portion 45^a can enter when shaft 25 and 80 therewith bracket 35 is depressed. A lever 50 is pivoted to the frame at 51, Figures 20 and 21 and is held in position by a spring actuated catch dog 52 which is also pivoted to the frame. Lever 50 is provided with a 85 stop piece 50^a which is opposite a bent portion 48^c of lever 48. If there is no envelope or other article above depression 1^a, bent portion 45^a of bar 45 will enter depression 1^a and bent portion 48^c will strike stop 50^a 90 and lock shaft 25 against further depression. If, however, an envelope or other article is opposite depression 1^a, bent portion 45^a will come in contact with it before bent portion 48^c strikes stop 50^a, and as bar 45 100 slides relative to bracket 35 and lever 48, projection 48^a will slide off lip 45^b of bar 45 and lever 48 will assume position shown in dotted lines at 48^a, Fig. 20. In this position bent portion 48^c clears stop 50^a and 105 shaft 25 is free to be depressed to its full allowance. Thus the mechanism just described will render the device automatically inoperative when it is not used to attach stamps upon an envelope or other suitable 110 article.

Lever 50 also has a knob 50^b attached to it which projects outside of the casing (see Figures 2, 3, 4, 6 and 7) and is operated by hand. If lever 50 is rotated into position shown in Figure 22, end 50^c will be brought in front of end of stud 10^a, Figures 10, 20 and 22 and as stamp guide members 7 and 8 are pivotally mounted on the frame 1 by a stud 9 (Figures 7, 8 and 13), 115 spring 11 will be prevented from pressing the stamp band upon the mouth of the moistening cell 21. In this position of lever 50 (Figure 22) stop 50^a clears 48^c (Fig. 20) and therefore if shaft 25 is depressed, 120 bar end 45^a will come in contact with bottom of depression 1^a causing lever 48 to assume position shown in Figure 22, and another bent portion 48^d is brought opposite stop 50^a which will permit shaft 25 130

to be depressed just enough to actuate feed lever 13, Figures 8 and 12, and knife element 42 will be prevented from shearing off stamps. In order to prevent 48^D from 5 rocking out of contact with stud 50^A Fig. 22, if plunger 25 should be violently depressed, head of screw 51 is made long enough to interfere with 48^C of lever 48, Figures 20 and 21, when they are in the position shown 10 in Figure 22. When pressure upon shaft 25 is released spring 44 will restore it to its normal position. Bar 45 is in contact at its upper end 45^D with the casing so that when shaft 25 and bracket 35 are restored 15 to their normal position bar 45 will also be restored to its normal position, being carried up against the casing by screws 46 and 47. Portion 48^E of lever 48, Figure 20 co-operates with lip 45^B of bar 45 20 so as to bring lever 48 back to its normal position. It is thus seen that when lever 50 is in position shown in Figure 22, each stroke of shaft 25 will feed forward one stamp without being moistened and register them upon counter 20 in a manner 25 already explained.

If, after any number of stamps have been fed forward, it is desired to shear them off, it is only necessary to turn lever 50 back 30 to its normal position (Figure 20) while shaft 25 is still in its depressed condition. This can be done easily by allowing shaft 25 to be restored slightly by spring 44 so as to separate bent portion 48^D from stop 35 50^A slightly. After lever 50 has been returned to its normal position the stroke of shaft 25 can be completed and the stamps clipped off. Thus this operation permits 40 of the counting and removal of any number of stamps desired without wetting them.

Now the mechanism for adjusting the guides for the envelope for the purpose of fastening a series of stamps upon it will be described. A guide member 55, Figures 26, 45 27 and 28 is slidably mounted upon base of frame 1. Another guide member 56 is also slidably fastened to the frame. Member 55 is guided by a cross piece 57 and a guide piece 58. Member 56 is slidably guided by 50 shoulder screw 59 and shoulder stud 60 which also passes through member 55 and is provided with a knurled nut 61. Bent portions 55^A and 56^A are provided to act as a gauge for the envelope when stamp is 55 fixed upon it. (See Figures 26, 27 and 28, 2, 3 and 4.) Thus if one stamp were to be affixed it would be fastened at "a" Figure 5. The guides can be adjusted in any position within their range and secured in 60 position by knurled nut 60, when it is desired to affix stamps at different places relative to edge of envelope. Member 55 is provided with another bent portion 55^B by which it can be manually shifted. Member 65 55 is also provided with notches 55^C and 55^D

co-operating with spring catch member 62. The distance between the notches is slightly greater than the height of a stamp and is for the purpose of fastening stamps one below the other as shown in Figure 5 at 70 "a and f." The other position of member 55 is shown at 55^A. Member 56 is also provided with notches 56^B, 56^C, 56^D, and they are spaced for securing stamps side by side as stamps a, b, and c Figure 5. A spring controlled roller lever co-operates with the notches and holds member 56 in place. Since it is frequently required to fasten two or more stamps upon an envelope automatic means are provided for advancing 80 member 56^A first forward 2 steps then backward 2 steps making it possible to affix 6 stamps side by side in the order a b c d e f Figure 5. Member 55 is manually operated. The mechanism for shifting member 56 85 will now be described: Two levers 65 and 66 are pivoted to the frame with shoulder screw 67 Figures 26, 28 and 30. Springs 68 and 68^A hold levers 65 and 66 against stops 69 and 70. At one end levers 65 and 90 66 pivotally support ratchet pawls 71 and 72, shown in Figures 26, 28 and 29. Pawl 72 is provided with a roller 72^A co-operating with a cam surface 55^D of member 55 best shown in Figure 29. A spring 73 95 presses upon pawl 72 as shown. Pawl 71 also is provided with a roller 71^A which co-operates with a bent portion 75^A of another member 75. A spring 74 presses upon pawl 71 as shown. Member 75 is a lever pivotally 100 supported on the frame by a shoulder screw 77. A sliding piece 78 is slidably guided on the frame (Figure 28) and is provided with a cam slot 78^A which co-operates with a pin 75^B on lever 75. A spring 80 acts upon 105 lever 75 as shown. Bent portion 78^B is provided for sliding member 78 manually in and out. Member 56 has a bent part 56^E provided with perforations 56^F, 56^G, 56^H and 110 56^K which co-operate with pawls 71 and 72. 110

Perforations 56^F and 56^G co-operate with pawl 72. Pawl 71 co-operates with perforations 56^H and 56^K. A lever 80^A is pivoted to the frame by shoulder screw 81 Figure 28 also Figures 6 and 7. One end of this lever 115 80 is U shaped and its two members 80^A and 80^B co-operate with levers 65 and 66 as shown in Figures 26, 28 and 30. A stud 35^E on bracket 35 Figure 28 also Figure 7, co-operates with lever 80 so that when shaft 120 25 is forced upward on the return stroke by spring 44 it will actuate lever 80^A bringing levers 65 and 66 into position shown in Figure 29.

The operation of the mechanism is as follows: When lever 75 is located by member 78 in position shown in Figure 29 pawl 71 will be held out of engagement of 56^E and perforations 56^H and 56^K by roller 71^A rolling upon member 75^A. Similarly pawl 72 is held 130

out of engagement of perforations 56^F and 56^G by roller 72^A as co-operating with cam member 55^D. When shaft 25 is forced up into normal position by spring 44 lever 80 being actuated by stud 35^E, will move levers 65 and 66 into position shown in Figure 29, and since pawls 71 and 72 are held out of engagement of member 56^E, no motion will be imparted to member 56. If, however, member 75 is in position shown in Figure 26, pawl 71 will be in engagement with side of perforation 56^K (Figure 27) so that on the upward stroke of shaft 25, pawl 71 will be actuated through lever 80 and lever 65 advancing member 56 one step to the right, roller on lever 63 engaging notch 56^G, Figure 26. Another operation of shaft 25 will advance member 56 another step to the right. Thus stamps will be affixed to the envelope in the following manner.

The envelope is placed in position in contact with guide members 55^A and 56^A, Figures 2, 3, 4, 26, 27 and 28 and knob 32 is depressed, resulting in a stamp being affixed at "a", Figure 5. On return stroke of knob 32 and shaft 25, guide member 56^A is advanced one step to the right as already explained. Now the envelope is manually shifted against guide 56^A and knob 32 again depressed causing a stamp to be affixed at "b", Figure 5. The above operations repeated will affix another stamp at "c". If more stamps are to be affixed, guide member 55 is shifted to a position shown at 55^D, Figure 26. A pin 75^D in lever 75, Figures 26, 28 and 29 projects and is engaged by bent portion 55^E shown in dotted lines, Figure 26, which causes lever 77 to assume position shown in Figure 29, thus guiding pawl 71 out of engagement of member 56^H. At the same time pawl 72 is disengaged from cam surface 55^D, Figure 29 and is brought into engagement with member 56^E to co-operate with perforations 56^F and 56^G.

Now if an envelope is held in contact with guide members 55^A and 56^A, on depression of knob 32 a stamp will be affixed at "d", Figure 5. Restoration of shaft 25 will shift member 56^A from its extreme right position one step to the left. Repeating above operations will result in stamps "e" and "f" being affixed, Figure 5. On affixing the last stamp "f", guide member 56 will have been restored to its initial position. To restore the guide mechanism to normal position, guide member 55 is manually pulled back to its position shown in full lines in Figure 26 and member 78 is manually pulled out to position shown in Figure 29. Now the mechanism is adjusted for affixing one stamp on an envelope at position "a", Figure 5. It is to be noted in connection with member 56 that it also is adjustable manually and can be secured in any position by knurled nut 61.

Now the combination lock device will be described. In Figures 2, 3 and 4, 84 represents a door held in place by clamp members 85 and 86, Figures 2 and 4. 87 is a sliding member slidably mounted on the inside of the casing 70 by lug portions 88 and 89. Three notches 87^A, 87^B and 87^C also are provided on the sliding member and a catch spring 90 to hold it in any of the three positions. Another lug portion 91 on door 84, Figures 2 and 3, cooperates with slide 87 so that in the position shown in Figure 2 the door is locked. Slide 87 is also provided with an upright portion 87^F, which is provided with a slotted portion 87^G for the purpose of guiding it by a 80 stud 93. A lug 35^H is provided on bracket 35, Figures 2, 3, 6, 7 and 21^A. A knob 94, Figures 2 and 3, is riveted to slide 87 and projects through a slot of the casing so that the slide 87 can be shifted either to the right or to 85 the left. When slide 87 is shifted to the right, upper portion of 87^F will be brought opposite lug 35^H thus locking shaft 25 and thereby knob 32 against depression, rendering the device inoperative. To open the 90 door, slide 87 is shifted to the left. A lock 92 cooperates with notches 87^E and 87^D, Fig. 2, and by said lock the slide 87 may be secured in either of its two positions, thus the door may be locked and the plunger 25 left 95 free to operate, or the door may be locked and the plunger 25 also locked, rendering the device inoperative. This latter feature is of value when it is desired to prevent the use of the device by unauthorized persons. 100

Having described my invention, what I claim as new and desire to secure by Letters Patent is:

1. In a stamp affixing apparatus, two adjustable guides mounted at right angles to each other, for positioning envelopes or other articles relative to the apparatus, means for shifting said guides, and a clamping device common to both guides for securing said guides in any desired position. 105

2. In a stamp affixing apparatus, two adjustable guides mounted to slide at right angles relative to each other for positioning envelopes or other articles relative to the apparatus, means for shifting said guides, 115 cooperating, yielding snap mechanism to locate said guides in predetermined positions for the fastening of one or more series of stamps side by side, and a clamping device for securing said guides in any desired position. 120

3. In a stamp affixing device, cooperating guides for positioning envelopes or other articles relative to the apparatus, and means under control of the operator for automatically shifting one of the guides, by the operation of the apparatus. 125

4. In a stamp affixing device adapted to fastening stamps on envelopes and other suitable articles, adjustable guides for man- 130

- ually locating the envelopes or articles, means for automatically shifting one of the said guides by operation of said device for the purpose of fastening a series of stamps side by side.
5. In a stamp affixing device adapted to fastening stamps on envelopes and other suitable articles, two adjustable guide means for manually locating envelopes or other articles, means for automatically shifting one of said guides by operation of the device for fastening a series of stamps side by side, means for manually shifting the other guide for fastening stamps adjacent to the first series and means for controlling the direction of shifting of the first mentioned guide from the second mentioned guide.
6. In a stamp affixing device, a reservoir, a capillary member connected with the reservoir, an element projecting through the orifice of the capillary member, means for bringing the stamps in contact with the orifice and means for actuating said element when the device is operated.
- 10 7. In a stamp affixing device, a reservoir, a capillary member connected with the reservoir, a yielding element projecting through the orifice of the capillary member, means for bringing the stamp in contact with the orifice, said means being adapted to actuate said yielding element.
- 15 8. In a stamp affixing device, a moistener adapted to moisten the stamps when brought in contact with it, means for holding stamps away from said moistener and means for automatically bringing the stamps in contact with the moistener by the actuation of the device.
- 20 9. In a stamp affixing device, a reservoir, a capillary member connected with the reservoir, means normally holding the stamps out of contact with the orifice of the capillary member, automatic means for bringing adhesive side of the stamps in contact with the orifice of the capillary member when operating device, and means for feeding the stamps in contact with the orifice.
- 25 10. In a stamp affixing device, a reservoir, an elongated capillary member connected with the reservoir, a blade element projecting through the orifice of the capillary member, means for depressing said element and bringing the adhesive side of the stamps in contact with the orifice.
- 30 11. A stamp affixing device, a reservoir, an elongated capillary member connected with the reservoir, a blade element projecting through the orifice of the capillary member, a valve device between the reservoir and the capillary member and means for opening the valve device when the blade element is depressed.
- 35 12. In a stamp affixing device, a reservoir, an elongated capillary member connected with the reservoir, a blade element project-

ing through the orifice of the capillary member, a valve device controlled from said blade element, means for actuating said element and bringing the adhesive side of the stamps in contact with the orifice, means for opening said valve when the blade element is actuated and means for feeding stamps in contact with the orifice.

13. In a stamp affixing apparatus, stamp feeding means, an affixing member for pressing the stamps upon an envelope or other article, a knife element mounted upon said affixing member and provision for rendering said knife element ineffective when the stamp feeding means is actuated.

14. In a stamp affixing apparatus, stamp feeding mechanism, cooperating knife elements and provision for rendering said knife elements ineffective, means for actuating the stamp feeding mechanism an indefinite number of times, said provision being also adapted to render the knife elements effective at the will of the operator to sever the stamps discharged by the feeding mechanism.

15. In a stamp affixing apparatus, stamp feeding mechanism, a cooperating moistening device, stamp detaching means and means adapted to render the stamp detaching means and the moistening device ineffective when the stamp feeding means is actuated.

16. In a stamp affixing apparatus, a moistener, a stamp feeding mechanism, means for holding the stamps away from the moistener, automatic means for bringing the stamps in contact with the moistener when the stamp feeding means is actuated and provision under control of the operator for locking the stamps out of contact with the moistener for feeding a desired number of stamps without being moistened.

17. In a stamp affixing apparatus, stamp feeding mechanism, an affixing member and means subject to the will of the operator for arresting the movement of said affixing member, after the stamp feeding mechanism has been actuated.

18. In a stamp affixing device, a stamp affixing member adapted to press a stamp upon an envelope or other article, means under control of the operator for arresting the movement of said affixing member before the completion of its stroke and provision for delivering stamps without affixing.

19. In a stamp affixing device, means for affixing stamps upon an envelope or other article, stamp detaching means, and provision under control of the operator for rendering the detaching means ineffective when the device is actuated.

20. In a stamp affixing device, stamp affixing means, knife elements cooperating with said stamp affixing means, and provision under control of the operator for

- preventing the cooperation of said knife elements when the device is actuated.
21. In a stamp affixing device, a stamp feeding mechanism, a moistener, an affixing member for pressing the adhesive stamps upon an envelope or other article and manual adjusting means for rendering the moistener ineffective when the stamp feeding means is actuated and for locking the stamp affixing member before the completion of its stroke. 5
22. In a stamp affixing apparatus, a moistening device, means for detaching the stamps and provision under control of the operator for rendering the moistening device and the detaching means ineffective, means for discharging a desired number of stamps in a dry condition and means for severing said stamps at the will of the operator. 15
23. In a stamp affixing apparatus, a moistening device, an affixing member, and means subject to the will of the operator for rendering the moistening device ineffective, said means being also adapted to arrest the movement of said affixing member before the completion of its stroke. 20
24. In a stamp affixing apparatus, stamp detaching means, an affixing member, and provision for rendering the stamp detaching means ineffective for discharging a desired number of stamps without being severed, said provision being also adapted to cause the arresting of the movement of the stamp affixing member before completion of its 35 stroke.
25. In a stamp affixing device, a stamp feeding mechanism, a moistener, means for detaching the stamp, stamp affixing means, a counting device to register the stamps fed by the feeding mechanism and manually operated means whereby the moistener, the detaching means and the affixing means are rendered ineffective when the stamp feeding means is repeatedly actuated, said last recited means being also adapted to render the detaching means effective to detach a desired number of stamps discharged by the feeding mechanism. 40
26. In a stamp affixing device, means for applying an envelope or other article to the device for the affixing of stamps, a member adapted to move into contact with the envelope or article by the initial actuation of the device and at a predetermined position relative to the attached stamps, and cooperating mechanism for causing the operation of the device to be arrested if the envelope or article is not opposite the path of said member. 50
27. In a stamp affixing device, means for applying an envelope or article to the device, means for actuating the device directly by the hand, a member adapted to move into contact with the envelope or article upon the initial actuation of said device, and mech- 55
- anism controlled by said member for causing the device to be inoperative if the envelope or article is not in the path of said member, said mechanism also causing the device to be operative if said member contacts with the envelope or article. 70
28. In combination with a device for the delivering and affixing of stamps, mechanism for rendering the device automatically inoperative when not applied to the affixing of stamps upon an envelope or other article and provision under control of the operator for causing the device to be operative and to deliver the stamps in a dry condition. 75
29. In a stamp affixing device, means for affixing stamps upon an envelope or other article, a member adapted to move into contact with the envelope or article after the device is actuated, and mechanism controlled from said member for causing the device to be ineffective for the affixing of stamps when the envelope or article is not in the path of said member. 80
30. In a stamp affixing device, means for actuating said device directly by the hand and mechanism responsive to the initial movement of the device and adapted to render the device automatically inoperative if the device is not applied to the affixing of stamps upon an envelope or other article. 90
31. In a stamp affixing device, guides for positioning an envelope or other article relative to the device, means for manually actuating said device, a member adapted to contact with the envelope or article upon the initial actuation of the device, mechanism controlled by said member for arresting the operation of said device if the envelope or article is not properly positioned relative to said guides. 95
32. In a stamp affixing device, means for affixing stamps to envelopes or other articles, means for delivering stamps in a dry condition, a registering device to register the discharged stamps, and provision for rendering the registering means ineffective when there are no stamps in the device. 100
33. In a stamp affixing device, a stamp affixing member provided with a universal connection and a cooperating spring device to cause said affixing member to yield in any plane opposite the attached stamp, and a knife element secured to said affixing member. 105
34. In a stamp affixing device, a stamp affixing member for pressing moistened stamps upon an envelope or other article, an independent spherical element cooperating with said affixing member, and a spring adapted to permit said affixing member to yield in any direction opposite the attached stamps. 120
35. In a device for delivering and affixing stamps, a casing, a door for said casing, a reciprocating plunger mounted to slide in 130

a vertical plane, means for operating the device by said plunger and a lock device whereby the door may be locked relative to said casing or the plunger locked against 5 operation simultaneously with the locking of the door at the will of the operator.

36. In a device for delivering and affixing stamps, a casing, a door for said casing, a reciprocating plunger mounted to slide in

a vertical plane, means for operating the 10 device by said plunger and a lock device adapted to lock the door relative to said casing and the plunger against operation.
